UNITED STATES PATENT OFFICE.

WILLIAM MULLEE, OF CHESTERVILLE, PENNSYLVANIA.

DESIGN FOR A BAND-COMB.

Specification forming part of Design No. 7,524, dated June 30, 1874; application filed April 25, 1874.
[Term of Patent 7 years.]

To all whom it may concern:

Be it known that I, WILLIAM MULLEE, of Chesterville, in the county of Chester and State of Pennsylvania, have invented a new and valuable Improvement in Designs for Combs; and I do hereby declare that the following is a full, clear, and exact description of the construction and operation of the same, reference being had to the annexed drawings making a part of this specification, and to the letters and figures of reference marked thereon.

Figure 1 of the drawing is a representation of my comb as applied, and Fig. 2 is a perspective view of the same. Fig. 3 is a plan view.

The nature of my design is fully represented in the accompanying drawings, to which reference is made.

A A designate two side combs, and B an intermediate comb, which three combs may be

of the same length, or of different lengths. The intermediate comb B is arranged out of line with respect to the side combs, and is connected to the latter by two arches, a a. The back edges of the combs may be straight, or they may be curved or ornamented in any fancy manner.

I prefer to give a rounded form to the comb B; but it may be straight, like the combs A A.

What I claim as my invention is—

The design for a band-comb formed by the portions A A B, connected by arches a a, substantially as described and shown.

In testimony that I claim the above I have hereunto subscribed my name in the presence of two witnesses.

WILLIAM MULLEE.
